DESIGN FOR A COMBINATION GRIDDLE
AND SKILLET

Arthur Beck, Chicago, Ill.

Application November 12, 1947, Serial No. 142,467

Term of patent 14 years

(Cl. D44—1)

To all whom it may concern:

Be it known that I, Arthur Beck, a citizen of the United States, residing at Chicago, in the county of Cook and States of Illinois, have invented a new, original, and ornamental Design for a Combination Griddle and Skillet, of which the following is a specification, reference being had to the accompanying drawing, forming part thereof.

In the drawing:

I claim:

The ornamental design for a combination griddle and skillet, as shown and described.

ARTHUR BECK.
